CLAIM

The ornamental design for an engine valve lifter having anti-rotation plug, as shown and described.

DESCRIPTION

FIG. 1 is a front perspective view of an engine valve lifter having anti-rotation plug in accordance with the present teachings.

FIG. 2 is a rear perspective view of the engine valve lifter having anti-rotation plug of FIG. 1.

FIG. 3 is a first side view of the engine valve lifter having anti-rotation plug of FIG. 1.

FIG. 4 is a front view of the engine valve lifter having anti-rotation plug of FIG. 1.

FIG. 5 is a second side view of the engine valve lifter having anti-rotation plug of FIG. 1.

FIG. 6 is a rear view of the engine valve lifter having anti-rotation plug of FIG. 1.

FIG. 7 is a bottom view of the engine valve lifter having anti-rotation plug of FIG. 1; and,

FIG. 8 is a top view of the engine valve lifter having anti-rotation plug of FIG. 1.

The broken line showing portions of the engine valve lifter having anti-rotation plug form no part of the claimed design.

1 Claim, 7 Drawing Sheets
